CLAIM

The ornamental design for a pulley machine, as shown and described.

DESCRIPTION

FIG. 1 is a front, top perspective view of the pulley machine, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area labeled 9 in FIG. 1; and,

FIG. 10 is an enlarged view of the area labeled 10 in FIG. 2.

The broken lines in the figures are for the purpose of illustrating portions of the pulley machine, which form no part of the claimed design.
